UNITED STATES PATENT OFFICE.

JOSEPH GEORGE TURNBULL, OF NEW YORK, N. Y., ASSIGNOR TO TURNBULL
ENGINEERING COMPANY, INC., A CORPORATION OF NEW YORK.

ELECTRIC FIXTURE.

1,172,229.

Specification of Letters Patent. Patented Feb. 15, 1916.

Application filed September 12, 1914. Serial No. 861,374.

To all whom it may concern:

Be it known that I, JOSEPH GEORGE TURNBULL, a citizen of the United States, residing in New York city, in the county of Bronx, State of New York, have invented certain new and useful Improvements in Electric Fixtures.

My invention relates more particularly to that class of electric fixtures which are known as outlet blocks or base blocks and the ground plate therefor.

The objects of my invention are to provide an outlet block which is easily, cheaply and simply made and constructed and which permits of its use and adaption in an economical and ready manner to more forms and uses than those today known, furthermore to provide a ground plate for use with such outlet block when desired, of simple construction and economical manufacture which can be readily and easily adopted to use as desired.

Further objects are to provide such fixtures of the class described which provide more efficient means in their respective uses and which do away with a large number of parts now in use.

With these and other objects in view, I have devised simple and novel constructions, which I will now describe, reference being made to the drawings in which like letters of reference indicate corresponding parts.

In the drawings, Figure 1 is a plan view of the outlet block. Fig. 2 is a section along lines 2—2 of Fig. 1, and Fig. 3 is a section along lines 3—3 of Fig. 1. Fig. 4 is a plan view of the supporting or "ground plate." Fig. 5 is a section on lines 5—5 of Fig. 4. Fig. 6 is a section of the clamping nipple, and Fig. 7 is a section of the lock-nut therefor. Fig. 8 shows in section the application of the ground plate and outlet block to a combination gas and electric fixture. Fig. 9 is a section view of the metal molding, and Fig. 10 is an end view thereof. Fig. 11 is a sectional view of the outlet block and ground plate applied to a straight electric outlet box. Fig. 12 shows an application of the outlet block when applied to a tap for a drop or portable light. Fig. 13 is a plan view of the base block, and Fig. 14 is a sectional view of the base block in use.

In the drawings A is the outlet block which may be made of porcelain, fiber, glass,

metal, glazed metal, or any non-conducting or glazed metal alloy of any shape desired. Preferably the shape is in conformity with that of the canopy to which it may be attached. I have shown it circular only as a matter of convenience.

In Figs. 1 and 2, B are channels through which the cables are inserted, the cables being preferably protected by metal molding. It is believed the use of metal molding, such as is commonly known as the "National" metal molding, is quite well known in the art, but for the sake of clearness I have shown in Fig. 9 a sectional view, and in Fig. 10 an end view of such molding, B' designating the upper and B'' the lower strips. The cables may be inserted through the channels B and out through the center opening C of the block A, or vice versa. Channels B have inwardly sloping bottom portions D, and the inner corners are rounded so as to permit of the more ready insertion of the cables. When the strips of metal molding are inserted in the channels, the edge of lower strip B'' comes in contact with the edge E which acts as a stop, the upper strip B' comes in contact with the edge F which similarly act as a stop and a consequent tight fit between the upper and lower strips is obtained. The stops E and F, by insuring a tight fit between the strips of metal molding, obviate the use of a bushing and permit of a smooth surface through which the cables are run.

When it is desired to attach the ground plate M directly to the ceiling or wherever else it is to be attached, the same is accomplished by use of screws inserted through the passages G. These passages G are particularly designed to permit of greater leeway in finding a purchase for the screws H when they are inserted therethrough as will appear hereafter. In Fig. 3 it will be noted that these passages are shown to taper inwardly toward the lower portion of the block, thereby permitting of the movement of the screw point in an area equal to that of the area of passage G at that end of the block and so permitting of the greater possibility of the screw finding a suitable purchase somewhere within that area, the screws, of course, being inserted at any angle to the vertical without shifting the block. The plate M may be called a ground plate

because it connects the metal moldings electrically as will appear hereafter, and thus by means of this plate all the conduits or moldings may be grounded. It will be readily seen that these passages may be made in various shapes, to allow a greater area for the screw point to find a purchase.

The amount of space provided for finding a purchase for the screw H'' as shown for instance in Fig. 12 depends only on the amount of taper of the sides of passage G ; the heads of the screw H being countersunk at J , in order to prohibit any grounding on the canopy, Fig. 8.

15 The exterior sides K of the channels B are ordinarily closed, but these closed portions are adapted to be readily and easily knocked out and the cable inserted through one or more channels as desired.

20 When it is desired to fit a crowfoot, or similar form of fixture, to the outlet block, the same is fastened to block A by means of suitable bolts and nuts H' inserted through holes L , located in the channels B . The 25 heads of said nuts are countersunk so as to give free slot movement and prohibit the possibility of any scraping along the channels B .

25 The ground plate M , shown in Fig. 4, is used particularly when it is desired to make 30 connections to a concealed outlet box or when the block is used with a straight or combination fixture. In this instance the plate M is secured to the gas pipe M' , Fig. 8, which passes through the outlet box as is usual.

35 The nipple N , employed to attach the ground plate, (Fig. 6) is threaded on its exterior side and is slotted at suitable places as 40 at O , so as to allow contraction for binding, and tapered so that when the lock-nut P is screwed thereon the inner sides of the nipple will bind upon whatever it circumscribes. 45 Ground plate M , when in use, is held between the head N' of the nipple and the lock-nut P , as shown in Fig. 8, and the outlet block is attached to the ground plate by screws inserted through the passages G into suitable screw-threaded openings Q in the 50 ground plate. One of the advantages of the passages G is thus readily seen from the convenience with which the screws H may be inserted therethrough and up through the holes Q of plate M .

55 Near the edge of the plate M are punched up portions R , through which is inserted the upper strip B' of the metal molding until it hits the turned up portion which acts as a stop therefor. The sides of the upper 60 strip B' are cut away as also shown in Fig. 9 so that only the top piece of the strip is forced beneath the punched up portions R in the plate M and lie on top of the latter against the turned up edge of the openings 65 T' . The position of the strips B' and B''

in Fig. 9 corresponds to the positions of the strips in Fig. 8. The lower strip of the metal molding is inserted into the block A until it hits the stop E and the cables are inserted through the portion inclosed by 70 said metal molding, through the channel B , and through the openings T' in the plate and spliced as desired. These splices may be in the outlet box S , concealed in the plaster W , or below it, as shown in Fig. 8. 75

When it is desired to use the block in connection with a straight electric outlet box, the ground plate M is secured between the head of the nipple N and the lock-nut P by attachment to supplemental nipple M'' , 80 which is secured to the box S' in the center thereof, and the crowfoot W' is attached to the outlet block A by means of bolts and nuts H' inserted through the passages L .

To the bottom portion U of the crowfoot 85 suitable attachments for a pendant or a stem for a straight electric may be secured.

When it is desired to use the outlet block in connection with a tap for a drop or portable light, no ground plate is needed, as is also the case in exposed wiring, and the rosette cap V is suitably secured to the block A by the bolts and nuts in the passages L , and the block itself is attached to the plaster or rafter W by means of the wood screws H'' . As shown in Fig. 12, the screws H'' are in an inclined position, as heretofore described. In Fig. 12 I have shown in dotted lines the well known arrangement, in a rosette cap, by which any strain or pull on the 90 portable light is not transmitted to the cables above. 100

When it is desired to use the block as a base block, it is preferably made smaller. In such an arrangement, the block A' has channels b which, however, are constructed to connect with channels c which run through the block; of course, a single central channel, as in Fig. 1, may be employed, but in this instance I prefer the construction shown in Fig. 14. The upper strip B' of metal molding abuts against a stop f and the lower strip B'' against a stop e when inserted, and should it be desired to carry the cables through two or more channels the pieces K are accordingly knocked out. The block is fastened to the wall W'' by means of suitable wood screws H'' , and switches or other devices are attached to the block by means of screws H' in the hole z in Fig. 13. 110 115 120

From the foregoing description taken in connection with the drawings, the operation of my invention will be readily understood and the advantages in obviating the use of a large number of small parts, such as single clamp bushings, set screws in the base plate, in the clamp bushings and in the case cover, insulation of canopy, insulating joint, hickey, etc., is easily apparent. 125

Having thus described some of the em- 130

bodiments of my invention, what I claim and desire to protect by Letters Patent is:—

1. In a lighting fixture, the combination of an outlet block, cable and molding therefor, said outlet block comprising channel portions through which the cable is readily insertible, grooves in said channel portions adapted to act as stops to the cable molding, closing means for each channel which are adapted to be easily knocked out so as to permit the use of one or more channels and means for permitting the ready attachment of said block as desired without shifting the block.
  2. In a lighting fixture, an outlet block comprising channel portions having downwardly sloping bottoms, grooves in said channel portions, closing means for each channel portion adapted to be readily knocked out, tapered holes and screws adapted to be inserted in said holes, the tapered holes permitting of the insertion of the screws in numerous positions so that the block may be attached as desired without shifting.
  3. In a lighting fixture, the combination of an outlet block, cable and cable molding, a ground plate therefor comprising bent up portions for holding strips of the said molding, turned-up portions adapted to act as stops for said strips of molding, openings for running the cable through the plate and means for readily attaching said plate to said block.
  4. A lighting fixture, of the class de-
- scribed, comprising in combination an outlet block, an outlet box and a ground plate adapted to be interposed between said block and box, means for fastening said plate to said box comprising a nipple having an externally tapered threaded slotted body portion, means attached to said box to which said nipple may be attached and a lock-nut for said nipple.
5. A lighting fixture, of the class described, comprising in combination a cable, cable moldings, an outlet block, a ground plate therefor and an outlet box, means for attaching said outlet box to said ground plate, said ground plate having a turned-up portion adapted to act as a stop to strips of said molding, said outlet block having grooves to act as stops to the other strips of said molding and said plate having a punched up portion adapted to have inserted therethrough strips of said molding, channels in said outlet block and openings in said ground plate for running the cable through threaded screw holes in said ground plate and means for readily attaching said outlet block to said ground plate through said threaded screw holes.

In testimony thereof, I have signed this specification in the presence of two subscribing witnesses.

JOSEPH GEORGE TURNBULL.
